INSIDE RELEASING MEANS FOR CLOSURES
OF VAULTS AND THE LIKEPaul S. Millice, Hamilton, Ohio, assignor to Her-
ring-Hall-Marvin Safe Company, New York,
N. Y., a corporation of New York

Application January 14, 1936, Serial No. 59,070

16 Claims. (Cl. 292—92)

The present invention relates to releasing means for the locking means of doors and other closures of safe vaults and other compartments, operable from the inside of the compartment, in which a person or persons may be accidentally or feloniously imprisoned, in order that the person or persons so imprisoned may prevent their suffocation, may give an alarm, or may effect their release.

It often happens that during a hold-up or robbery, the person or persons in the place in which the hold-up or robbery is taking place, are forced to enter a vault or other compartment, and are locked therein while the felony is being committed, to prevent interference with the felony, to prevent the giving of an alarm, and to permit the felon or felons to make their escape. Frequently, too, persons are locked in safe vaults and other compartments accidentally, and at such times it often happens that no one is present who can open the door or other closure thereof.

It is an object of my invention therefore, to provide novel means whereby the door or other closure of a compartment may be opened from the inside of the compartment by a person imprisoned in the compartment.

It is the object of my invention further, to provide novel mechanism operating independently of the lock for the closure whereby the lock may be by-passed and the closure opened from the inside of a compartment; and, further, to provide inside releasing mechanism, simple in construction, which can readily be attached to existing closure locking mechanisms.

The present invention consists in novel means whereby to interrupt the train of locking mechanism from the inside of the compartment locked thereby, by a person who may be accidentally or feloniously imprisoned in the compartment; further, in novel tripping mechanism operable from the inside of the compartment for disengaging a part of the locking mechanism whereby the locking means for a closure of the compartment may be unlocked from the inside of the compartment; and, further, in providing novel tripping means between the lock and the bolt work for a closure operable from the inside of the compartment closed by said closure.

The invention is exemplified as applied to the entrance door of a safe vault, although it is obvious that the same may be applied to other closures and to closures of other compartments.

In the drawings:

Fig. 1 is an elevational view of the inside of a

vault door having my improved releasing means applied thereto, the wall of the safe vault being shown partly broken away, and the bolt work and hinging means being shown in dotted lines.

Fig. 2 is a horizontal sectional view of the same, taken on the irregular line 2—2 of Fig. 1, and partly broken away.

Fig. 3 is an enlarged view of a detail of my improved device, taken in section on the line 6—6 of Fig. 2, showing the parts in locked relation.

Fig. 4 is a horizontal section of the same taken on the line 4—4 of Fig. 3, and showing the latch member and the plunger in assumed positions in dotted lines.

Fig. 5 is a vertical section of the same taken on the line 5—5 of Fig. 3.

Fig. 6 is a vertical sectional view, showing the bolt operating means and the locking means therefor in bolted and locked relation, taken in the plane of the irregular line 6—6 of Fig. 2, and partly broken away.

Fig. 7 is a similar view, showing the bolt operating means and the locking means therefor in unlocked and unbolted relation as operated from the inside of the compartment.

Fig. 8 is a vertical section of a modification of the invention, taken on the line 8—8 of Fig. 9; and,

Fig. 9 is a horizontal section of the same taken on the line 9—9 of Fig. 8, and showing the latch member and the plunger in assumed positions in dotted lines.

An opening 11 in the wall 12 of a usual vault is closed by a vault door 13, the flange 14 of which seats in a rabbet 15 in the margin of the wall of the opening 11. Usual bolts 16 carried by the door are movable lengthwise and may be moved past the edge of the door and into holes 17 in the inner face of the wall of the opening 11 to hold the door closed. The compartment in the inside of the vault is designated by the numeral 18.

The vault door exemplified comprises a front plate 21, a Z-shaped marginal edge piece 22 being rigidly secured, as by welding, to the margin of the front plate at its four edges, and extending continuously around the door. The intermediate web 23 of the Z-shaped edge piece 22 is provided with openings 24, forming bearings for the door bolts 16. These door bolts are shown at the swinging edge of the door, the door being hinged at its opposite edge to the opposite wall 25 of the door opening 11, by usual hinges 26, stationary lugs 27 on the door entering keeper

holes 28 in said wall 12 for additionally holding the door in locked relation.

A usual inside cover plate 29 rests on the inner edges of the Z-shaped pieces 22 and is suitably 5 secured in place. It spans the space between the edge pieces at the respective margins of the door.

The bolts are rigidly connected by an actuating bar 31, which is located in rabbets 32 in the inner ends of said bolts, the bolts being fixed 10 to said bar by rivets 33. Links 34 are pivoted to said bar at one of their ends by shoulder rivets 35 and to one of the corners of bell crank plates 36, 37, at their other ends by shoulder rivets 38. The plates 36, 37 are pivoted to the inner face 15 of the front plate 21 on usual studs 39, 40, secured to said front plate.

Links 43, 44, are respectively pivoted at their outer ends to another of the corners of the bell crank plates by shoulder rivets 45, 46, and at 20 their adjacent ends to an operating arm 47 by shoulder rivets 48, 49.

A mounting plate 51 is fastened to the front plate 21 of the door and is spaced therefrom as by having spacing collars 52 received between 25 said mounting plate and said front plate. Screws 53 passing through said mounting plate and said spacing collars are threaded into the front plate and firmly position the mounting plate.

30 The double operating arm 47 for the bolt work of the door is securely fastened to the inner end of a rock shaft 55, the outer end of this rock shaft being provided with an operating handle 56. The operating arm is provided with a hole 35 57 shaped to fit the inner square end 58 of the rock shaft. A washer 59 is located on this inner end and bears against the operating arm, which in turn bears upon the shoulders 60 formed by the squaring of said inner end of the rock shaft. 40 A nut 61 is threaded over the reduced threaded extension 62 of said rock shaft and clamps the operating arm securely to the rock shaft.

The rock shaft 55 is journaled in a bearing 65 in the front plate 21 of the door and in a flanged 45 bushing 66 received in a bearing 67 in the mounting plate 51. The rockable operating arm 47 and shoulders 68 and 69, respectively on the rock shaft 55 and on the bushing 66, coacting respectively with the front plate and the mounting 50 plate, serve to position said rock shaft endwise.

When the operating arm 47 has been rocked to move the door bolts 16 into the holes provided for them, it is desired to lock the bolts on this position. For thus locking said bolts a lock 71 55 is provided, shown fastened by usual means to the mounting plate. This lock is shown as of the permutation type, the kind most commonly used in the present construction, but a key-operated or other lock may be used.

60 The lock exemplified is provided with an operating dial 72 for rotating suitable tumblers, to align their slots, whereupon a bar 73 on one end of a connecting link 74 drops into said slots, and a hook 75 on said end drops into a coacting 65 slot in one of the tumblers, as is usual in such locks, so that, upon further rotation of the dial, or upon rotation of the key of a key-lock, if the latter be employed, a lock bolt 76 is actuated 70 to move the lock bolt into obstructing relation with the operating arm of the bolt work of the door. The other end of the connecting link is pivoted to the lock bolt by a shoulder rivet 77. In such relation, rotation of the dial, or of the key, 75 in the opposite direction withdraws the lock bolt

from the operating arm of the bolt work of the door.

In the present construction the lock bolt, when moved into locking position, as shown in Fig. 6, 5 is inserted into the space between a lug 78, on the operating arm, and a block 79 secured to the mounting plate 51. This securely locks the door. To open the door it is necessary to operate the lock mechanism by means of the dial 72, or of the key if a key lock be employed, to 10 withdraw the lock bolt and free the operating arm 47, which permits release operation of the door bolt work by operation of the handle 56.

A stop 81 is fixed to the mounting plate 51 for limiting the extent of movement of the operating arm 47 in locking and unlocking directions. The lug 78 on the operating arm contacts the stop when the door bolt work has been moved into bolted position. The operating arm is provided with a tail 82 which contacts the stop when the door bolt work has been moved into unbolted position and the bolt work is unbolted.

There is an auxiliary operating arm 83 operatively contacting the rockable arm 47 for unbolting the door bolt work from the inside of the 25 vault. The auxiliary operating arm is fixed to the outer end of an inner rock shaft 84. The inner end of this rock shaft is provided with an operating handle 85 at the inner face of the cover plate 29 and operable from the inside of 30 the vault or compartment. (Figs. 1 and 2).

The auxiliary operating arm is provided with a hole 57' shaped to fit the outer square end 58' of the inner rock shaft. A washer 59' is located over this outer end and bears against the auxiliary operating arm, which in turn bears upon the shoulders 60' formed by the squaring of said outer end of the rock shaft. A nut 61' is threaded over the reduced threaded extension 62' of the inner rock shaft and clamps the auxiliary operating arm securely to this rock shaft.

The inner rock shaft is journaled in a flanged bushing 89 received in an opening 90 in the inner plate 29 of the door. The flange provides a shoulder 91 seating against the inner face of 45 said inner plate. A collar 92 is threaded over said bushing and serves to clamp said inner plate between said shoulder and the inner end of said collar.

The means herein exemplified for releasing 50 the door bolt work from the inside of the vault or compartment will now be described.

There is a releasable member in the train of locking mechanism for interrupting this train and permitting release of the door bolt work. 55 This releasable member is exemplified as operatively located between the lock and the bolt work, being shown as a latch member 101, exemplified as mounted on the lock bolt 76, although it is obvious that it may be otherwise supported, as on the operating arm 47, for instance, as shown in the modification exemplified in Figs. 8 and 9, without departing from the spirit of my invention as set forth in the accompanying claims.

The mounting of the latch member may be had 65 by providing it with lugs 102 which coact snugly with lugs 103 on the outer end of the lock bolt 76, a pivot pin 104 having snug bearing in said lugs. A coil spring 105 is located about said pin in a recess 106 between the lugs 103. The spring 70 has one end 107 located in a hole 108 in the end of the body of the lock bolt, another end 109 of the spring bearing against the outer face of the latch member. The body of the bolt and the latch member are provided with coacting contact 75

faces 110, 111, to arrest resilient movement of the latch member in a position so that the latch member is normally located in obstructing locking position between the locking mechanism and the bolt work. The corner of the latch member on the side of its pivot opposite to its shoulder is shown cut away, as at 112, to permit swinging of the latch member. (Fig. 4).

A plunger 115 is axially slidable in a sleeve 116 located in an opening 117 in the inner plate 29 and having a flange 118 at one side of said plate. A spacing collar 119 is located about said sleeve at the other side of said plate. The sleeve is secured to the plate by a nut 120 threaded over the threaded end of the sleeve, clamping said flange and said spacing collar to the plate.

The plunger 115 is provided at the inner end thereof with a head 121 which also serves to limit outward movement of the plunger, a cotter pin 122 received through said plunger limiting inward movement of the same.

When pushed outwardly, that is, toward the outside of the door, the plunger 115 is arranged to contact the latch member 101 and to move the same out of range of the locking lug 78, so that the operating arm 47 may be moved by the inside handle 85 to unbolt the bolt work of the door and enable the door to be opened from the inside of the vault or other compartment for release of anyone who may be imprisoned therein. This lug may be provided with a clearance face 123 to enable it to move alongside of the latch member.

Figs. 8 and 9 represent a modification, in which the latch member is pivoted to the operating arm and forms the locking lug, similar parts being designated by similar reference numerals raised to the series 200. In order to insure actuation of the latch member throughout its movement with the operating arm, the latch member of the modification may be provided with a tail 125, which may ride upon the outer end of the plunger during operation of the door bolt work, and to prevent the plunger being moved into interfering relation with the operating arm.

The inner handle 85 and the head 121 of the plunger 115 are the only operating parts of the present exemplification of my invention which are at the inner face of the door. While the head 121 is under ordinary circumstances hardly noticeable, its location makes it possible for even an uninstructed person to open the door from the inside. The natural reaction of a person locked in the vault is to attempt to turn the handle with one hand while pushing on the door with the other and during such attempt the plunger will be pressed, either accidentally or intentionally. Even a person becoming frantic and struggling wildly to open the door, would undoubtedly at some time during his struggles accidentally operate the plunger and the inner handle correctly to free himself.

The plunger 115 or inner operating part for the latch member 101 is retracted by the spring 105 when the latch member reassumes its normal position. While I have shown the inner operating part for the latch member as a plunger, it is obvious that it may assume other forms, and that other changes in construction may be made, without departing from the spirit of my invention as set forth in the accompanying claims.

I claim:

1. In a door locking mechanism, the combination of bolt means for said door, an operating handle for said bolt means, and a lock for said bolt means comprising a lock bolt having a body portion and a transversely movable portion thereon, said lock bolt arranged to be moved into obstructing relation with said bolt means when said door is bolted, and means to move said movable portion of said lock bolt transversely independently of said lock and body portion of said lock bolt out of obstructing relation with said bolt means whereby said door may be unbolted by manipulation of said handle. 10
2. In a door locking mechanism, the combination of bolt means for said door, an operating handle for said bolt means, a lock having an operable part provided with an independently movable element for engaging said bolt means and locking said bolt means against movement, and means to actuate said movable element out of engaging relation with said bolt means independently of said lock for disengaging said independently movable element from said bolt means 20 during locked relation of said lock. 25
3. In a door locking mechanism, the combination of bolt means for said door, an operating arm for said bolt means, a handle for said operating arm whereby said operating arm may be moved for bolting and unbolting said door, and a lock having a lock bolt and a movable extension pivoted to said lock bolt, said lock bolt arranged to be moved for movement of said extension into and out of obstructing relation 30 with said operating arm by manipulation of said lock, and said movable extension arranged to be swung relatively to said lock bolt out of obstructing relation with said operating arm while said lock bolt is in locking position. 35
4. In a door locking mechanism, the combination of bolt means for said door, an operating arm for said bolt means, a handle for said operating arm whereby said operating arm may be moved for bolting and unbolting said door, 40 a lock having a lock bolt and a movable extension pivoted to said lock bolt, said lock bolt arranged to be moved for movement of said extension into and out of obstructing relation with said operating arm by manipulation of said lock, and means independent of said lock for moving said movable extension out of obstructing relation with said operating arm while said lock is in locking position. 45
5. In closure locking means for a compartment, the combination of a lock comprising a bolt and a coacting part for said bolt, means whereby to operate said lock from the outside of said compartment, said bolt and said coacting part being a pair of members, one of said members comprising a movable element coacting with the other of said members when said lock is in locked condition, and means operable solely from the inside of said compartment independent of said first-named means to place said movable element in unlocking relation to said other of said members whereby to open said closure from the inside of said compartment during such locked condition of said lock. 50
6. In combination, in means to lock the door 65 of a vault, a lock comprising a bolt, and a door latching part coacting with said bolt, said bolt and said door latching part being a pair of members, one of said members comprising an independently movable locking element coacting 70 with the other of said members to lock the door when said bolt is in locking position, said independently movable locking element movable independently of movement by said lock bolt into release relation with said other of said members, 75

and means operable from the inside of the vault for so independently moving said independently movable locking element for unlocking the door in an emergency.

5 7. In inside releasing means for a closure of a compartment, the combination of a lock comprising a lock bolt, a bolt work for the closure comprising a part coacting with said lock bolt, said lock bolt movable by said lock into and out 10 of the path of said part for locking and unlocking said bolt work, said lock bolt and said part constituting a pair of coacting members one of which is movable out of the path of the other independent of said movement by said lock for unlocking 15 said bolt work, and means for so moving said movable member from the inside of said compartment.

20 8. In inside releasing means of the character described, the combination of a lock comprising a lock bolt, a coacting part therefor operating with the bolt work, said lock arranged to move said lock bolt into and out of locking relation with said coacting part, said lock bolt and said coacting part constituting a pair of members one 25 of which is movable out of locked relation independent of said lock actuation, means operable from the inside of the compartment for so moving said movable member, and resilient means for said movable member resisting such movement of said movable member.

25 9. Emergency release means for the bolt work of the door of a vault, comprising a lock and its lock bolt and an actuating arm for the bolt work, said actuating arm provided with a locking lug, 30 said lock bolt having a locking part, said locking part and said locking lug forming a pair of coacting locking members one of which is movable out of range of the other during locked relation between said part and said lug, and means operable at the inside of the door to move such movable member out of the path of the other of said coacting locking members to release said bolt work during locking position of said lock bolt.

35 10. Emergency release means for the bolt work of a closure of a compartment, comprising a lock and its lock bolt and an actuating arm for the bolt work, said actuating arm provided with a locking part and said bolt having a coacting locking part one of which locking parts is movable 40 out of range of the other of said locking parts during locked relation of said lock bolt and arm, and a plunger at the inside of said closure to move said movable locking part out of such range of the other of said coacting locking parts to release 45 said bolt work actuating arm during locking position of said lock bolt.

45 11. Emergency release means for the bolt work of a closure of a compartment, comprising a lock and its lock bolt and an actuating arm for the bolt work, said actuating arm provided with a locking part and said bolt having a coacting locking part, one of which locking parts is movable 50 out of range of the other of said locking parts during locked relation of said lock bolt and arm, a plunger at the inside of said closure to move said movable locking part out of such range of the other of said coacting locking parts to release 55 said bolt work actuating arm during locking position of said lock bolt, and a handle at the inside of said closure for operating said bolt work.

55 12. Emergency release means for the bolt work of a closure of a compartment, comprising a lock and its lock bolt and an actuating arm for the bolt work, said actuating arm provided with a

locking part and said bolt having a coacting locking part, one of which locking parts is movable from normal locking position out of range of the other of said locking parts during locked relation of said lock bolt and arm, a plunger at the 5 inside of said closure to move said movable locking part out of such range of the other of said coacting locking parts to release said bolt work actuating arm during locking position of said lock bolt, and a spring retracting said movable 10 locking part to normal position.

15 13. Emergency release means for the bolt work of a closure of a compartment, comprising a lock and its lock bolt and an actuating arm for the bolt work, said actuating arm provided with a locking part and said bolt having a coacting locking part, one of which locking parts is pivotally movable from normal locking position out of range of the other of said locking parts during locked relation of said lock bolt and arm, a 20 plunger at the inside of said closure to move said movable locking part out of such range of the other of said coacting locking parts to release said bolt work actuating arm during locking position of said lock bolt, and a spring between said 25 movable locking part and the part to which it is pivoted to urge said movable locking part into normal position, said movable locking part and said last-named part provided with coacting shoulders to stop said movable locking part in its 30 correct normal locking position.

14. Emergency release means for the bolt work of a closure of a compartment, comprising a lock and its lock bolt and an actuating arm for the bolt work, said actuating arm provided with a locking part and said bolt having a locking part pivoted thereto and coacting with said first-named locking part, a block fixed to said closure in spaced relation to said first-named locking part when said arm is in its bolt projecting position, said pivoted locking part located in said space during locking position of said lock bolt, said pivoted locking part movable on its pivot out of range of said first-named locking part for release of said actuating arm during locked relation of said lock, and means at the inside of said closure to so move said pivoted locking part on its pivot.

15. Emergency release means for the bolt work of a closure of a compartment, comprising a lock and its lock bolt and an actuating arm for the bolt work, said actuating arm provided with a locking part and said bolt having a coacting locking part, one of which locking parts is movable out of range of the other of said locking parts for release of said bolt work actuating arm during locked relation of said lock bolt and arm, and means at the inside of said closure to so move said movable locking part.

16. Emergency release means for the bolt work of a closure of a compartment, comprising a lock and its lock bolt and an actuating arm for the bolt work, said actuating arm provided with a locking part and said lock bolt having a coacting locking part, one of which locking parts is pivotally movable out of range of movement of the other of said locking parts for locating said locking parts side by side upon unbolting of said bolt work during locked relation of said lock, one of said locking parts recessed for accommodating the other of said locking parts when so located side by side, and means at the inside of said closure to pivotally move said pivotally movable locking part.
